UNITED STATES PATENT OFFICE.

MARY PHIPPS, OF MITCHELLVILLE, MARYLAND.

DESIGN FOR A DOLL.

Application filed May 19, 1925. Serial No. 13,490. Term of patent 14 years.

To all whom it may concern:

Be it known that I, MARY PHIPPS, a citizen of the United States, residing at Mitchellville, in the county of Prince Georges, State of Maryland, have invented a new, original, and ornamental Design for Doll, of which the following is a specification, reference being had to the accompanying drawing, forming part thereof.

In the accompanying drawing the figure is a perspective view illustrating a doll embodying the invention.

I claim:

The ornamental design for a doll as shown.

MARY PHIPPS.
